United States Patent Office

Des. 215,651
Patented Oct. 21, 1969

215,651

RECREATIONAL VEHICLE BODY OR SIMILAR ARTICLE

James O. Hoff, Westminster, Calif., assignor, by mesne assignments, to Berry Mini-“T,” Long Beach, Calif., a corporation of California

Filed Sept. 30, 1968, Ser. No. 13,775

Term of patent 14 years

Int. Cl. D12—08

U.S. Cl. D14—3

FIG. 1.

FIG. 2.

FIG. 3.

FIG. 4.

FIG. 5.

FIG. 1 is a perspective view of a recreational vehicle body incorporating my new design;

FIG. 2 is a front view thereof;

FIG. 3 is a rear view thereof;

FIG. 4 is a plan view thereof; and

FIG. 5 is a side view thereof.

The elements shown in broken lines are included for illustrative purposes only.

I claim:

The ornamental design for a recreational vehicle body or similar article, substantially as shown and described.
